WALL AND CORNER GUIDE

Edward L. Betterton, El Cajon, Calif.

Application October 15, 1954, Serial No. 462,575

4 Claims. (Cl. 33—85)

This invention relates to improvements in bricklayers' guides, and more particularly to a novel and more efficient and practical device of this kind which is especially devised for building corners, but can also be used in building straight walls between corners, of either brick or blocks of varying sizes.

The primary object of the invention is to provide a device of the character indicated above which is of simpler and more easily usable form, which is more quickly and accurately adjustable to different conditions, and which enables more accurate and uniform work in less time and with less effort on the part of a worker.

Other important objects and advantageous features of the invention will be apparent from the following description and the accompanying drawings, wherein, for purposes of illustration only, a specific embodiment of the invention is set forth in detail.

In the drawings:

Figure 1 is an inside perspective view of a device in accordance with the present invention, showing application thereof to an upper course of a corner;

Figure 2 is an outside perspective view, on a reduced scale, showing application of the device to a foundation;

Figure 3 is a fragmentary and contracted inside elevation, showing application of the device to an upper course of a straight wall;

Figure 4 is a horizontal sectional view taken through a lower part of the device of Figure 3;

Figure 5 is an enlarged fragmentary vertical transverse section taken on the line 5—5 of Figure 3; and,

Figure 6 is a similarly enlarged vertical transverse section taken on the line 6—6 of Figure 3.

Referring in detail to the drawings, wherein like numerals designate like parts throughout the several views, the illustrated corner guide, generally designated 9, comprises two similar right triangular sections 10, 10.

Each section 10 comprises an angle iron base member 11, a channel altitude member 12, and a hypotenuse or diagonal member 13, secured together in rigid relation to each other by any suitable means, such as welding.

Each base member 11 has a horizontal flange 14 and a vertical flange 15 on the outer edge of the horizontal flange 14. The altitude member 12 has spaced parallel outer and inner flanges 16 and 17, respectively. The diagonal or hypotenuse member 13 has a vertical flange 18 and a laterally inwardly directed flange 19.

The altitude members 12, 12 are hingedly connected together, preferably by a piano hinge 20 which is secured to the altitude members at the intersection of the inner flanges 16 with the web 21 of the members 12, 12. The resultant hinging of the sections 10 together not only provides for compactly collapsing the sections 10 upon each other for storage and transportation, but provides for angulating the sections 10, 10 relative to each other to conform to different building corner angles.

The diagonal members 13 and the altitude members 12 have horizontally aligned notch and slot formations

2

which are parallel to the base members 11 for holding a level guide line 22. The line 22 has weights, such as plumb bobs 23, 23 on its opposite ends, which are preferably adjustable along the line 22, the principal function of the weights 23 being to tighten the line 22 and eliminate slack therein.

The said notch and slot formations include V-shaped notches 24 and 25 in the diagonal member flanges 18 and 19, respectively, and downwardly angulated slots 26 in the inner flanges 16 of the altitude members 13. The lower ends of the slots 26 terminate in rounded openings 27 through which the line 22 can be readily slid. The said notches and slots are spaced along the altitude members 12, 12 and the diagonal members 13, 13 at intervals corresponding to desired heights of different courses of bricks or blocks. The line 22 is disposed in the described notches and slots with the weight equipped ends thereof outside of the hypotenuse members 13, 13 when the device is used as in Figure 1; and inside of the hypotenuse members 13, 13 when used as in Figure 2.

When the device is used on a corner foundation 28, as shown in Figure 2, the foundation being composed of angularly related members 29 and 30, the sections 10, 10 of the device are supported upon the members 29 and 30 by means of several adjustable levelling assemblies 31, located on the base members 11, 11 at points intermediate of and spaced from the altitude members 12, 12 and the outer ends of the base members 11.

As shown in Figure 5, each levelling assembly comprises a vertical bolt 32, threaded upwardly through the horizontal flange 14 of a base member 11 and having an enlarged head 33 on its lower end. An annular spacer 34 is circumscribed on the bolt 32 between the head 33 and the underside of the flange 14. A spacer sleeve 35 is circumscribed on the bolt 32 above and spaced from the flange 14 and a helical spring 36 is circumscribed on the bolt 32 and is compressed between the flange 14 and the lower end of the sleeve 35. A levelling lug 37 has at one end a hole 38 rotatably receiving the bolt 32 at the upper end of the sleeve 35 and a free end portion 39. A nut 40 is threaded on the bolt 32 and bears down upon the levelling lug 37.

As a course of bricks or blocks 41 is laid upon the foundation 28, with the levelling lugs 37 turned out of the way, the levelling lugs are turned to overlie the top of the course, as shown in Figures 1 and 2. As the corner walls are built up, the device 9 is lifted, where desirable, and the levelling lugs 37 placed upon the tops of upper courses 41.

For preventing falling of the device 9 from position, the base members 11, 11 are provided at their outer or free ends with clamp assemblies 42, 42, each of which, as shown in Figure 6, comprises a bolt 43 threaded downwardly through a base member flange 14 and having a wrench head 44 on its upper end. Threaded on an intermediate part of the bolt 43 are upper and lower adjusting nuts 45 and 46, respectively. These nuts engage the upper and lower sides of a clamp plate 47, with the bolt 43 passing through a longitudinal slot 48 provided in the inner end of the clamp plate 47. The outer end of the clamp plate 47 has thereon a depending flange 49. The slot 48 provides for adjusting the clamp plate 47 for different widths of bricks or blocks. As shown in Figure 6, the clamp plates 47, when properly adjusted, rest upon the top of a wall course with the depending flange engaged with a side of the course with the free edge of the base member flange 14 engaged with the opposite side of the course, whereby transverse shifting of the base member 11 concerned is precluded.

The base members 11, 11 have additional levelling bolts 50, 50 at their inner ends near the altitude members 12, 12. The levelling bolts 50, 50 are threaded

downwardly through the base member flanges 14, 14 and have heads 51 on their upper ends.

The device 9 is used at the outside edge of a corner, as shown in Figure 2, with the weights 23 at the inner sides of the diagonal members 13, 13, the line 22 being located at the outer side of the altitude members 12, 12 and disposed in notches 52 provided in the flanges 16, 16 of the altitude members 12, 12 where they meet the webs 21. The line 22 is disposed in the slots 26 in the altitude members 12, 12 when the weights 23, 23 are located at the outer sides of the diagonal members 13, 13, as shown in Figure 1.

Figures 3 and 4 show the device 9 in use on a straight wall, and, in this instance the sections 10, 10 are hinged into mutually aligned positions along the wall or foundation, the installation being in this case otherwise the same as for a corner.

As a wall or a corner is built up, the device 9 being left in position on a foundation or lower course, the line 22 is raised and positioned in selected upper ones of the described notches and/or slots, so as to serve as a guide line for the tops of succeeding courses.

What is claimed is:

1. In a wall and corner guide, a pair of similar right triangular sections each having a base member, an altitude member, and a diagonal member, said members being in fixed relation to each other, a line having plumb bobs on its opposite ends, said line having an intermediate portion and end portions including said opposite ends, first means on said altitude members and second means on said diagonal members for suspending said line with its intermediate portion parallel to said base members and its end portions depending toward said base members, and levelling means comprising levelling assemblies spaced from each other along said base members, said levelling assemblies comprising vertically adjustable elements having lower ends disposed below the level of said base members.

2. In a wall and corner guide, a pair of similar right triangular sections each having a base member, an altitude member, and a diagonal member, said members being in fixed relation to each other, a line having plumb bobs on its opposite ends, said line having an intermediate portion and end portions including said opposite ends, first means on said altitude members and second means on said diagonal members for suspending said line with its intermediate portion parallel to said base mem-

bers and its end portions depending toward said base members, and levelling means comprising levelling assemblies spaced from each other along said base members, said levelling assemblies comprising vertically adjustable elements having lower ends disposed below the level of said base members and levelling lugs threaded on said elements above said base members.

3. In a wall and corner guide, a pair of similar right triangular sections each having a base member, an altitude member, and a diagonal member, said members being in fixed relation to each other, a line having plumb bobs on its opposite ends, said line having an intermediate portion and end portions including said opposite ends, first means on said altitude members and second means on said diagonal members for suspending said line with its intermediate portion parallel to said base members, and levelling means comprising levelling assemblies spaced from each other along said base members, said levelling assemblies comprising vertically adjustable elements having lower ends disposed below the level of said base members, said levelling means including levelling bolts threaded downwardly through said base members near said altitude members and having lower ends positioned below said base members.

4. In a wall and corner guide, a pair of similar right triangular sections each having a base member, an altitude member, and a diagonal member, said members being in fixed relation to each other, a line having plumb bobs on its opposite ends, said line having an intermediate portion and end portions including said opposite ends, first means on said altitude members and second means on said diagonal members for suspending said line with its intermediate portion parallel to said base members and its end portions depending toward said base members, and levelling means comprising levelling assemblies spaced from each other along said base members, said levelling assemblies comprising vertically adjustable elements having lower ends disposed below the level of said base members and spring means tensioning said elements in one direction.
